UNITED STATES PATENT OFFICE.

ROBERT S. LAWRENCE, OF BOSTON, MASSACHUSETTS, ASSIGNOR TO CONSOLIDATED INVENTORS CORPORATION, OF BOSTON, MASSACHUSETTS, A CORPORATION OF SOUTH DAKOTA.

CAR-VENTILATOR.

SPECIFICATION forming part of Letters Patent No. 760,795, dated May 24, 1904.

Application filed August 14, 1903. Serial No. 169,512. (No model.)

To all whom it may concern:

Be it known that I, ROBERT S. LAWRENCE, a citizen of the United States, residing at Boston, in the county of Suffolk and State of Massachusetts, have invented an Improvement in Car-Ventilators, of which the following description, in connection with the accompanying drawings, is a specification, like numerals on the drawings representing like parts.

10 This invention relates to a car-ventilator of that class wherein the necessary suction for drawing the foul air from the interior of the car is produced by the movement of the car itself.

15 The particular features wherein the invention resides will be more fully hereinafter described and then pointed out in the claims.

Figure 1 is a side elevation of a car having my improved ventilator applied thereto. Fig. 20 2 is a top plan view of the swiveled double mouthpiece of the ventilator. Fig. 3 is a section through the top of the car on the line xz , Fig. 1. Fig. 4 is a modification; and Fig. 5 is a section through the roof of the car and on 25 an enlarged scale, showing further details of construction.

30 3 designates a pipe which extends longitudinally of the car on its interior and which is preferably situated near the top of the car, where the impure air accumulates. This pipe is open to the interior of the car, preferably by making it perforated, as best shown in Fig. 5, and at one or more places it extends through the roof of the car. Swiveled to each exposed 35 end of the pipe is a vacuum or suction mouthpiece or cowl, which operates to create the necessary suction during movement of the car. In this embodiment of my invention the pipe 3 is screwed into an ordinary **T** 4, which in 40 turn is screwed into a thimble 5, which passes through the car-roof. The upper end of the thimble is provided with an enlarged bore, which receives the stem 6 of the vacuum-mouthpiece, said stem resting upon a suitable 45 washer 7, of leather or other packing material. I prefer to employ the double mouthpiece or cowl, (best illustrated in Fig. 2,) which comprises the two mouthpieces 8 and

9, in which case the stem 6 will be branched, and one branch, 10, will lead to each mouthpiece. The two mouthpieces terminate in the single plate 11, which has apertures therein to correspond with the opening in the mouthpieces. It is my intention to cast or otherwise form the plate 11, the mouthpieces 8 and 9, and the branch stem 6 all in one piece. Since the stem 6 merely sits in the enlarged bore of the thimble, it is obvious that the entire mouthpiece or cowl structure can be turned about said stem as an axis and made to face toward either end of the car.

When the device is in operation, the mouthpiece will be placed to open toward the back of the car, or in a direction opposite to the movement of the car. When in this position, 65 the motion of the car will create sufficient suction, so that the air in the car will be drawn through the perforations in the pipe 3 and out through the mouthpieces. To hold the mouthpiece in either adjusted position, I have 70 provided the plate 11 at each end with a catch 16, and I place coöperating latches 17 on the top of the car. With this construction the mouthpiece may be swung in to face either direction, and when in proper position one of 75 the latches 17 will automatically engage the corresponding catch 16, and thus hold said mouthpiece properly positioned. The latches are shown as having knobs or thumb-pieces 18 thereon by means of which they may be 80 released.

19 designates a damper situated in the stem of the mouthpiece. This damper is mounted on a rock-shaft 20, which is suitably journaled in the thimble and which has extending from 85 its end the arms 22, from each of which depends an operating-cord 21. These cords pass through the roof of the car, so that they can be operated from the interior thereof. A pull on one of the cords will open the damper, 90 while a pull on the other cord will close the damper, as will be obvious from an inspection of the drawings.

To permit the stem 6 to turn in the thimble, I provide said stem with a slot extending partially about the same, through which slot the

rock-shaft 20 extends, said slot permitting a free turning movement of the stem without disturbing the damper.

I have herein shown each of the pipes 3 as 5 having a mouthpiece connected thereto at each end thereof, said mouthpieces being situated at opposite ends of the car. One or more pipes 3 with its mouthpieces may be employed, according to the size and speed of the 10 car. I have herein illustrated two such pipes, one at each side of the car at its upper end, and each pipe has a mouthpiece at each end thereof, as described above. The pipes and 15 ventilator may be located in any convenient position on the top of the car.

In Fig. 4 I have illustrated a slightly-different form of mouthpiece, wherein the plate 11' is circular instead of rectangular, as shown in Fig. 3. In other respects the modification 20 shown in Fig. 4 is the same as the construction already described.

In the operation of the device the rapid movement of the car through the air causes a 25 partial vacuum to be formed in each mouthpiece, with the result that the air is drawn from the interior of the car through the perforations in the pipe 3 and out through the mouthpieces. Since the heated impure air 30 always rises to the top of the car, it follows that with my ventilator it is possible to take such air out of the car as fast as it rises to the top thereof, with the result that the air in the car may be kept absolutely pure.

Various changes may be made in the 35 construction of the device without departing from the invention expressed in the appended claims.

Having described my invention, what I 40 claim as new, and desire to secure by Letters Patent, is—

1. In a car-ventilator, a perforated pipe extending longitudinally of the car on its interior, a thimble secured to said pipe and extending vertically through the car-roof, a horizontally-arranged suction mouthpiece or cowl 45 having a vertical stem or neck which is swiveled to said thimble, a pivoted damper supported by said thimble and situated within the stem or neck, and means on the interior of the car for operating said damper.

2. In a car-ventilator, a perforated pipe extending longitudinally of the car on its interior,

rior, a thimble secured to said pipe and extending vertically through the car-roof, a horizontally-arranged suction mouthpiece or cowl 55 having a vertical stem or neck which sets into the upper end of the thimble and is swiveled thereto, and a damper for the cowl, said damper operating to hold the cowl from vertical movement with reference to the thimble. 60

3. In a car-ventilator, a thimble passing through the car-roof, a suction mouthpiece or cowl, having a vertical stem or neck, which sets into the upper end of the thimble and is swiveled therein, a pivoted damper within said 65 stem, said damper having a stem extending through a slot in the cowl-stem whereby the cowl may be turned.

4. In a car-ventilator, a thimble fixedly secured to and passing through the car-roof, a 70 suction mouthpiece or cowl having a vertical stem or neck setting into the upper end of the thimble and supported thereby for turning movement, a damper within the neck of the cowl, or mouthpiece, said damper having a 75 stem extending through a circumferential slot in the neck of the cowl and through an aperture of the thimble.

5. In a car-ventilator, a cowl comprising a plate having two apertures, two cone-shaped 80 suction-mouthpieces extending laterally from said plate, said mouthpieces being alined with said apertures and each having communication with a vertical cowl stem or neck, and a thimble extending through the car-roof and to 85 which said neck is swiveled.

6. In a car-ventilator, a cowl comprising a plate having two apertures, two cone-shaped suction-mouthpieces extending laterally from 90 said plate, said mouthpieces being alined with said apertures and each having communication with a vertical cowl stem or neck, a thimble extending through the car-roof and to which 95 said neck is swiveled, and a locking-lug secured to said plate, and a locking-latch on the car-roof to coöperate with said lug and hold the cowl in its adjusted position.

In testimony whereof I have signed my name to this specification in the presence of two subscribing witnesses.

ROBERT S. LAWRENCE.
